Des. 232,381
Patented Aug. 13, 1974

232,381

PHOTOGRAPHIC PRINT DRYER

John N. Harman, Jr., La Canada, and James S. Livingood, Reseda, Calif., assignors to Drewry Photocolor Corporation, Burbank, Calif.

Filed Mar. 27, 1972, Ser. No. 238,740

Term of patent 14 years

Int. Cl. D16—04

U.S. Cl. D61—1 Q

FIG.4

FIG.5

FIG. 1 is a front elevational view of a photographic print dryer showing our new design;

FIG. 2 is a right side elevational view thereof;

FIG. 3 is a top plan view thereof;

FIG. 4 is a left side elevational view thereof; and

FIG. 5 is a rear elevational view thereof.

We claim:

The ornamental design for a photographic print dryer, substantially as shown.
